UNITED STATES PATENT OFFICE.

LEONARD HOLT, OF CONCORD, NEW HAMPSHIRE.

HOOP-CUTTING MACHINE.

SPECIFICATION forming part of Letters Patent No. 252,666, dated January 24, 1882.

Application filed November 23, 1881. (No model.)

To all whom it may concern:

Be it known that I, LEONARD HOLT, a citizen of the United States, residing at Concord, in the county of Merrimack and State of New Hampshire, have invented certain new and useful Improvements in Hoop-Cutting Machines; and I do hereby declare that the following is a full, clear, and exact description of the same, reference being had to the annexed drawings, 10 making a part of this specification, and to the letters and figures of reference marked thereon.

My invention relates to improvements in hoop-cutting machines for cutting what are known as "half round hoops" from an ordinary round pole with the bark left on.

In my machine a longitudinal section of proper dimensions for a finished hoop is cut from an ordinary hoop-pole by revolving circular knives or cutters in a single passage through the machine, leaving the outside bark unbroken and the inside of the hoop smooth and complete, without requiring further dressing or planing. I attain these objects by the mechanism and construction substantially as shown in the accompanying drawings, in which—

Figure 1 is a perspective view of a machine embodying my invention; and Fig. 2 is a detail view of the circular cutters, showing the manner of connecting them to the arbors.

30 The frame H, with its supports g, and standards K K form the frame-work of the machine, adapted to carry the operating parts.

In the standards K K, upon each side, suitable recesses are made for the insertion of Bab- 35 bitt journal-boxes for bearing the journals of the arbors f f', upon which the cutters are secured, and these arbors project beyond the standards K K to allow the affixing of the requisite gearing to communicate power.

40 Between the standards upon the lower arbor, f, is fixed a circular cutter, A, with sharpened edge, and directly above it a similar cutter, A', is fixed upon the arbor f', the lowermost point in the circumference of the upper cutter, A', being as near as possible to the uppermost point in the circumference of the lower cutter, A, without actual contact, their cutting-edges 45 revolving in the same perpendicular line. These cutters are fixed upon their respective arbors 50 at any desirable point between the standards K K, and are held rigidly in position by sleeves

n n, of suitable material, to insure the necessary support for the circular cutters inclosed between them. From the point of contact with the sides of the knives A A' the sleeves taper in opposite directions nearly the whole length of the arbors between the standards K K, and assist in strengthening the arbors near the center, where it is most desired. These sleeves are bored through the center, so as to slip on 55 the arbors against the cutters after they are placed in position, and are then secured by nuts a at their outside ends, screwed tightly against the ends of the sleeves, as shown in Fig. 2. These nuts are turned directly upon 60 the arbors and secured by threads cut for that purpose at suitable distances from either end.

At one side of the cutters A A' an upright roller, B, is sustained in a vertical position by journals at top and bottom suitably secured to 70 the frame-work which connects the standards K K.

The machine may be operated by hand by means of the crank e, attached to the end of the shaft p, or by other power by means of the belt-pulley d upon the same shaft. This shaft p is supported by journal-bearings upon the frame H, and may have connected to it a suitable pinion, meshing with the teeth upon a large gear-wheel, s, in the usual manner. The gear-wheel 75 s is rigidly secured to one end of the arbor f, which carries the lower cutter, A, and upon the opposite end of said arbor is a gear-wheel or pinion, b, engaging with the teeth of a pinion, c, upon the end of the upper arbor, f'. 80

When it is desired to operate the machine it is set in motion and one end of a round hoop-pole, such as forms the usual material for that purpose, is pressed against the projecting front edges of the circular cutters at a point midway 85 between the sleeves n n, its side resting lightly against the upright roller B. The cutters A A', turning in a direction toward the rear of the machine, draw the pole forward as the cutting proceeds, and serve to make the machine 90 self-feeding without the use of feed-rolls either in front of or behind the cutters. The entire absence of feed-rolls or bearings of any kind except the cutters allows the operator to move the pole which is being cut in any direction; and the 95 diameter of the cutters being such that a sufficient space is left between the sleeves n n to 100

admit the passage of material of sizes commonly used in making hoops, the operator can at will change the direction of the cutting-line by a slight movement of the pole, so as to follow the outline of a crooked and irregular pole through all its sinuosities, and obtain a hoop of the same thickness throughout its entire length.

Additional hoops may be cut from the same pole by turning a different section to the cutters, and repassing it through the machine, so long as a sufficient width of bark remains to make a complete hoop. The space between the roller B and the sides of the cutters A A', Fig. 2, determines the thickness of the hoop, and the roller B, being adjustable laterally at each end, may be set so as to cut hoops of any desired thickness.

It will be noticed in Fig. 2 that the edges of the circular cutters A A' are beveled so as to cut a flat and smooth surface upon the inside of the hoop. I am thus enabled to produce a

hoop with a finished inside surface, so as to obviate for most purposes the necessity for any further planing or dressing.

What I claim as my invention is—

1. In a hoop-cutting machine, the combination, with the upright adjustable roller B, of the circular cutters A A', having their edges beveled or inclined, substantially as and for the purpose set forth.

2. In a hoop-cutting machine, the upright adjustable roller B, in combination with the screw-threaded arbors f f', carrying circular cutters A A', secured thereon by sleeves n and screw-nuts a, substantially as and for the purpose specified.

In testimony that I claim the above I have hereunto subscribed my name in the presence of two witnesses.

LEONARD HOLT.
